(**) Term: **14 Years**

(57) **CLAIM**

(21) Appl. No.: **29/162,464**

The ornamental design for a soft sleeve for fast copper pipe joint, as shown and described.

(22) Filed: **Jun. 18, 2002**

DESCRIPTION

(51) LOC (7) Cl. **23-01**
(52) U.S. Cl. **D23/262**
(58) Field of Search D23/259, 262;
285/34, 35, 235

FIG. 1 shows a perspective view of the present design.
FIG. 2 shows a front elevational view of the present design.
FIG. 3 shows a rear elevational view of the present design.
FIG. 4 shows a left elevational view of the present design.
FIG. 5 shows a right elevational view of the present design.
FIG. 6 shows a top plan view of the present design; and,
FIG. 7 shows a bottom plan view of the present design.
